RUG KNIFE OR SIMILAR ARTICLE

Glen C. Dyment, 47C Washington St., Concord, N.H., and John E. Martin, Box 171, Andover, N.H.

Filed Apr. 28, 1965, Ser. No. 85,008

Term of patent 14 years

(Cl. D22—3)

FIG. 1

The dominant portions of the design reside in the full line showing on the drawing.

We claim:

The ornamental design for a rug knife or similar article, substantially as shown and described.
